UNITED STATES PATENT OFFICE.

GEORGE W. GOFF, OF EAST HAMPTON, CONNECTICUT, ASSIGNOR TO EAST HAMPTON BELL COMPANY, OF SAME PLACE.

DESIGN FOR SLEIGH-BELLS.

Specification forming part of Design No. **11,529**, dated December 2, 1879; application filed August 26, 1879.
[Term of patent 3½ years.]

To all whom it may concern:

Be it known that I, GEORGE W. GOFF, of East Hampton, in the county of Middlesex and State of Connecticut, have invented a new Design for Sleigh-Bells; and I do hereby declare the following, when taken in connection with the accompanying drawings and the letters of reference marked thereon, to be a full, clear, and exact description of the same, and which said drawings constitute part of this specification, and represent, in—

Figure 1, a perspective view; Fig. 2, a vertical section.

This invention relates to a design for the class of bells commonly called "sleigh-bells;" and the design consists in the peculiar configuration of the bell, as shown in the accompanying illustration, and hereinafter described.

The form of the bell is such as to present several sides with clearly-defined angles at the intersection of the sides, the line of the

angles running from the center at the top to the center at the bottom. Each side is composed of two curves in vertical section, producing two arcs of circles, the one springing from the top center downward, the other from the center bottom upward, and so as to form a clearly-defined horizontal line where the two curves of each side meet, and at the largest diameter of the bell, as seen in Fig. 1.

I claim—

The herein-described design for bells, consisting of several sides, each side in vertical section, composed of arcs of two different circles, forming a clearly-defined horizontal line at the point where the two arcs meet, as shown in the accompanying illustration.

GEORGE W. GOFF.
